UNITED STATES PATENT OFFICE.

EDWARD M. WHARTON AND JOHN W. JONES, OF GREENVILLE, SOUTH CAROLINA.

HARNESS STAND AND STOP MOTION FOR LOOMS.

Application filed July 11, 1921. Serial No. 483,800.

To all whom it may concern:

Be it known that we, EDWARD M. WHARTON and JOHN W. JONES, citizens of the United States, residing at Greenville, in the 5 county of Greenville and State of South Carolina, have invented new and useful Improvements in Harness Stands and Stop Motions for Looms, of which the following is a specification.

10 This invention relates to a harness stand and stop motion for looms, the principal object of the invention being to provide means for automatically stopping the loom if the harness should break or stretch or any 15 part of its assembly give way so as to interfere with the movement of the shuttle.

Another object of the invention is to provide means whereby the attachment can be made adjustable to conform to the loom 20 upon which it is used.

Another object of the invention is to provide means whereby the device will operate with the ordinary stop motion of the loom.

Another object is to provide a stand upon 25 which the harness will rest when any portion of the harness (its straps, hooks or equipment) breaks or stretches, thus causing the harness hame to drop from its usual position onto said stand so that said stand 30 will prevent the harness from dropping onto the floor.

This invention also consists in certain other features of construction and in the combination and arrangement of the several 35 parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:—

Figure 1 is an end view, largely diagrammatic, showing our invention in use with a 45 loom.

Figure 2 is an enlarged sectional view showing the invention in use.

Figure 3 is a view of the attachment 50 itself.

Figures 4 and 5 are fragmentary views showing a modification.

As shown in these views the attachment 55 comprises the base 1 which is adapted to be secured fast to the floor. An upright 2 is connected with said base and an upright 3

is adjustably secured to the upright 2 by the bolts and slots 4. The upper end of upright 3 is of fork shape with the extremities of the arms of the fork bent upwardly 60 to form the vertical parts 5. One of these vertical parts is provided with a hole 6 and the other with a slot 7 for forming bearings for the crank rod 8, this rod being 65 suitably secured in position. One end of the rod is extended, as at 9, and this extension is provided with a bent part 10 which passes through a block 11 and is adjustably secured thereto by the bolt 12. An arm 13 is adjustably secured to the block by the 70 bolt 14. A stud 15 projects from one of the vertical parts 5 and engages the crank part of the rod 8 to hold the same in position. We prefer to make one of the end pieces of the crank of rod 8 longer than the other, 75 as shown in Figure 3, so as to place the bight of the crank substantially parallel with the lower edges of the harness, it being understood that said lower edges of the harness are not in a horizontal plane but 80 are arranged in an inclined plane.

As shown in Figures 1 and 2, one of these devices is placed beneath the loom directly under the harness and one at each end of the harness. The devices are adjusted in 85 height to suit the loom, by means of the bolts and slots 4 and the crank of rod 8 rests at an angle of about 15°, this rod being held in this position by the stud 15. Arm 13 extends at an angle of about 15° in an opposite direction from the crank of rod 8 so that it will not interfere with the normal 90 operation of the loom. However, if any portion of the harness should break or if it should stretch beyond its natural position 95 it will fall on the rod 8, thus causing the rod to tilt and move arm 13 upwardly into the stop motion comb and thus automatically stop the loom.

Our invention will prevent damaging of 100 the cloth in process of manufacture and thus eliminate "seconds." The device will not interfere with the proper running of the loom nor will it conflict with any stop motion now in use as it will only come into 105 operation when any part of the harness breaks or stretches and thus interfere with the movement of the shuttle.

Figures 4 and 5 show a modification in which the arm 13' is provided with a hook 110 at its upper end for engaging an arm 13'' which is bolted to the stop motion comb.

In other respects this form of the device is similar to that first described.

It is thought from the foregoing description that the advantages and novel features 5 of the invention will be readily apparent.

We desire it to be understood that we may make changes in the construction and in the combination and arrangement of the several parts, provided that such changes fall 10 within the scope of the appended claims.

What we claim is:—

1. A heddle stop motion device comprising a stand, a rod rotatably mounted therein and provided with a crank part, the bight 15 of which is of considerable length and is adapted to be placed under the harness and an arm connected with one end of the rod for engaging the stop motion when the crank is engaged by the harness.
- 20 2. A heddle stop motion device comprising a stand, a rod rotatably mounted therein

and provided with a crank part, the bight of which is of considerable length and is adapted to be placed under the harness and an arm adjustably connected with one end of 25 the rod for engaging the stop motion when the crank is engaged by the harness.

3. A heddle stop motion device comprising a stand, having a forked upper end, a rod having parts rotatably mounted in the 30 prongs of the fork, said rod having a crank part located between the prongs, the bight of which is adapted to be placed under the harness and an arm connected with one end of the rod for engaging the stop motion of 35 the loom when the rod is moved by the harness engaging the crank part.

In testimony whereof we affix our signatures.

EDWARD M. WHARTON.
JOHN W. JONES.
